Primary Examiner — Mark A Goodwin(74) *Attorney, Agent, or Firm* — Bereskin & Parr LLP/S.E.N.C.R.L., s.r.l.(57) **CLAIM**

The ornamental design for a tractor feed strip, as shown and described.

DESCRIPTION

FIG. 1 is a perspective view of a tractor feed strip; FIG. 2 is a top view thereof; FIG. 3 is a bottom view thereof; FIG. 4 is a first side view thereof; FIG. 5 is a second side view thereof; FIG. 6 is a first end view thereof; FIG. 7 is a second end view thereof; FIG. 8 is an enlarged view of area 8 in FIG. 7; and, FIG. 9 is a top view thereof, shown in use condition attached to edges of a retractable assembly shown in broken line that forms no part of the claimed design.

The claimed design is shown with a symbolic break in its length. The appearance of any portion of the tractor feed strip between the break lines forms no part of the claimed design.

The broken lines in FIG. 9 illustrate the retractable assembly and form no part of the claimed design.
